TELEPHONE SYSTEM

Otho D. Grandstaff, Chicago, Ill., assignor to Associated Electric Laboratories, Inc., Chicago, Ill., a corporation of Delaware

Application November 14, 1936, Serial No. 110,864

13 Claims. (Cl. 179—16)

The present invention relates to telephone systems in general, but is concerned more particularly with telephone systems wherein automatic switches employed in the setting up of connections are controlled by alternating current pulses transmitted over the talking conductors of inter-exchange toll or long distance lines. The object of the invention is the production of a new and improved auxiliary unit known as a tone unit, one of which tone units is associated with each end of a two-way alternating-current-dialling toll line, being interconnected with a two-way impulse repeater.

The tone unit disclosed herein is a direct improvement on the tone unit illustrated in Fig. 4 of the drawings in Patent 2,040,637, granted May 12, 1936 to John Wicks. The improved tone unit may be used to replace the tone unit shown in Fig. 4 of the Wicks patent, as the leads incoming to the tone unit disclosed herein are similar in function and number to the leads interconnecting the tone unit in the Wicks patent with the associated repeater. The new tone unit, however, was provided particularly for cooperation with new and improved impulse repeaters of the type shown in the application of John Wicks, Serial Number 109,671, filed November 9, 1936. In this Wicks application, the present tone unit is fully illustrated and is rather completely described in order to bring out the novel features of the system disclosed in the said Wicks application.

The tone unit disclosed herein contains features of improvement over the corresponding equipment in the Wicks patent referred to, including the following features:

(1) In order to improve the signal reception, in addition to the main tuner which is resonant at the signal carrier frequency, a second tuner is employed which is resonant at a frequency lying below the signal carrier frequency and also at a frequency lying above the signal carrier frequency. This additional double-peak tuner is associated through suitable circuit connections with the apparatus so that current flowing therethrough opposes the action of the current flowing through the main tuner. One desirable result of this arrangement is that sharp frequency cut-off points are obtained, while a uniform frequency response is secured over a band of the desired width lying between these points. Additionally, by arranging that the double-peak tuner passes enough current at the signal carrier frequency when a very strong signal arrives, the opposing effect of the current from the double peak tuner

is sufficient to limit the response and thereby lessen the tendency to overload the succeeding apparatus. The detecting or rectifying apparatus which succeeds the tuners is so arranged that the potential built up at the double-peak tuner must overcome a substantial adverse bias before detection or rectification of current therefrom can occur, whereby the opposing effect from the double-peak tuner is entirely absent in the event that weak signals are being received, as it is undesirable that a weak signal be diminished in any way by the opposing effect of the double-peak tuner.

(2) The general method of detecting utilized in the Wicks patent referred to has been retained in the present disclosure, but has been improved to enable a wider signal range to be accommodated. The signal rectification is carried out through a tube of the diode type, and the rectified potential is supplied to the grid element of an amplifier tube so related to the diode tube that the plate current controlled by the rectified signals varies directly with the signal strength instead of varying inversely as in the prior structure. By this arrangement, the responding relay is normally restored and operates responsive to the rise of current when a signal is received. Tests reveal that this arrangement gives greatly superior results when the wide range of signal strength met with in practice is taken into account.

(3) In order to secure a more reliable operation of the incoming signal relay, which responds only when the received carrier current is modulated at the predetermined modulating frequency, the output of the impulse amplifier is further amplified by a signal amplifier before being passed to the circuit of the incoming signal relay. By this arrangement a strong response to the incoming signal relay is assured over the maximum range of input signal strength.

(4) An improved method of modulating the transmitted carrier frequency has been employed. Whereas the prior arrangement utilized a supply of plate current taken directly from the source of modulating alternating current, the present arrangement supplies modulating potential to a grid element of the amplifier tube lying between the screen grid and the anode element, while the carrier frequency is impressed in the usual way through the application of a potential at carrier frequency to the control grid of the tube.

By choosing an amplifier tube having the desired characteristics, the modulated carrier current flows at substantially full strength through

out half of each cycle, abruptly rising to full strength and abruptly falling to zero strength as the modulation alternating-current potential applied to the modulation grid element of the tube reverses in polarity.

Other features of the disclosure will become more apparent as the description progresses.

Referring now to the drawing, the improved tone unit is shown diagrammatically therein, together with conductors leading through cable 1200 assumed to extend to an associated impulse repeater as disclosed in the pending Wicks application hereinbefore referred to.

Since it is undesirable in telephone practice that any of the trunk or line equipment be disabled upon the failure of the commercial power supply, the tone unit here illustrated has been arranged as far as possible to be independent of a temporary power failure. The heaters of the vacuum tubes are supplied with current from the 48-volt exchange battery, and the plate and screen-grid current is obtained from a separate 130-volt storage battery. The 1000-cycle potential normally impressed on the common lead 1242 is preferably obtained from a 1000-cycle generator operated from the 48-volt exchange battery, while the 60-cycle, 40-volt modulation potential impressed on the common lead 1241 is preferably obtained normally from the 60-cycle source of commercial current, with automatic switching arrangements effective in the event of a failure of the commercial source of power to switch this lead over to a stand-by 60-cycle generator which is automatically started into operation drawing power from the exchange battery. By the grid modulation arrangement disclosed, only a negligible amount of 60-cycle power need be generated by a local generator when the commercial power fails.

40 The signals received over the associated toll line come into the tone unit through receiving conductors 1162 of the cable 1200, while the transmitted signals go out over sending conductors 1161 of the cable 1200 to the conductors of the toll line.

Direction-transfer relay 1202 is normally energized over direction-transfer conductor 1165 of cable 1200, through contacts of key 1234. With direction-transfer relay 1202 in its normally energized condition, the tone unit is conditioned for the reception of signals. This relay is restored to adapt the tone unit for transmission. Modulation-cut-off relay 1201 is controlled over modulation-cut-off conductor 1167 of the cable 1200 to substitute ground potential for the 60-cycle modulation conductor 1241 when unmodulated signals are to be transmitted.

Pulse-cut-in relay 1204 is controlled over pulse-cut-in lead 1166 of the cable 1200 to substitute incoming-impulse relay 1203 for plate-impedance coil 1207 when the tone unit is to be conditioned for the reception of dial pulses. These dial pulses are repeated over the dial-in conductor 1164 of the cable 1200 for an incoming repeating relay 65 of the associated impulse repeater.

The incoming-signal relay 1205 transmits its signals over the signal-in conductor 1163 of the cable 1200 to a signal-repeating relay of the associated impulse repeater.

70 It may be pointed out that receiving leads 1162 of the cable 1200 correspond to receiving leads 391 and 392, Fig. 4 of the previously mentioned Patent 2,040,637, granted to Wicks; sending leads 1161 correspond to sending leads 393 and 394 of the Wicks patent; modulation-cut-off relay 1201

and modulation-cut-off conductor 1167 correspond respectively to relay 324 and lead 395; direction-transfer relay 1202 and the associated cable conductor 1165 correspond respectively to relay 325 and conductor 396 in the Wicks patent; pulse-cut-in relay 1204 and the associated cable conductor 1166 correspond respectively to relay 401 and the associated lead in the Wicks patent; and the signal-in and dial-in leads 1163 and 1164 correspond respectively to the leads in the 10 said Wicks patent which are controlled by relays 404 and 402, respectively.

The tone unit includes vacuum tubes 1211, 1212, 1213, and 1214. The tubes 1211 and 1213 are of the type known as 6C6, each being provided with a heater of a nominal rating of 6.3 volts, at which voltage it draws .3 ampere. Tube 1212 is a double-diode tube arranged to function as a differential detector of incoming signals. This tube is of the type known as 6H6, being provided with 20 a two-section heating which requires a potential difference of 6.3 volts to pass .3 ampere through it.

The signal amplifier 1214 is a tube of the type known as 43, having a 25-volt heater which also is rated to draw .3 ampere. The heaters of these 25 tubes are all connected in series, as shown, and they are normally drawing current in the circuit with the 4-ohm resistor 1225 through contacts of the normally-actuated key 1237, the connection with the negative pole of the 48-pole exchange battery being made through the 10-ohm test relay 1033. This test relay is normally actuated, but is permitted to restore and close a circuit for the signal lamp 1236 in the event that any one of the tubes is removed from its socket 30 or develops a burned out or broken heater element. The potential-drop along the heater circuit from the negative pole of the 48-volt battery is used at various points for grid-biasing purposes, as will be pointed out.

40 Tube 1211 is used as a two-way amplifier, being used as an outgoing amplifier and modulator in the transmission of signals to the associated toll line. This tube is provided with a cathode as indicated, adjacent which is shown the control grid. Adjacent the control grid is the screen grid which is supplied with positive potential from the 130-volt source of plate current through the 50,000-ohm resistor 1227, being by-passed to ground by the .1 mf. condenser 1228. Between 45 the control grid and the plate, there is shown the suppressor grid (used as a modulation grid) which is connected either to ground potential or to the 60-cycle, 40-volt lead 1241, depending upon the actuated or restored condition of relays 1201 and 1202.

For the reception of signals, the primary winding of the 1 to 30 ratio step-up transformer 1224 is connected to the receiving conductors 1162 through the two illustrated .1 mf. condensers. 60 The secondary winding of this transformer is normally connected to control the potential applied to the control grid of tube 1211, as a negative biasing potential of 1.2 volts being applied to the control grid of tube 1211 by virtue of the 65 1.2 volt drop across the 4-ohm resistor 1225.

With direction-transfer relay 1202 in operated position, as it normally is, the secondary winding of the 30 to 1 ratio step-down transformer 1217 is connected across the leads 1243 and 1244. The 70 inductance coil 1223 is connected across the leads 1243 and 1244 in series with the .04 mf. condenser 1222, which condenser is shunted by the indicated trimmer condenser of such capacity as to render the couple series-resonant at 1000 cycles, 75

whereby a relatively high potential is placed on the right-hand anode of the differential detector 1212 by the voltage drop across coil 1223 when a 5 1000-cycle current is being received and amplified by tube 1211.

In order to enable the system to respond to impulses of 1000 cycles, plus or minus an amount equal to about sixty cycles so as to allow for the reception of 60-cycle-modulated, 1000 cycle 10 pulses, and to cut off sharply when frequencies higher or lower than the allowable band are received, the inductance coils 1219 and 1221, with their associated tuning condensers are arranged to form what may be termed a double-peak 15 tuner. This tuner peaks at 900 cycles and at 1100 cycles. The 900- and 1100-cycle peaks are in addition to the peak produced by the inductance coil 1223 and its associated condensers, as previously pointed out. Coil 1221, in series 20 with the tuning condenser 1220 (assisted by the associated trimmer condenser), is resonant at 1100 cycles, provided substantially no current is permitted to flow through the shunt condenser 1218. The last named condenser has a capacity 25 of about .01 mf. Current of 1100 cycles is substantially prevented from flowing through condenser 1218 by the shunt-resonant effect of coil 1219 and the associated shunt condensers, as this system is shunt-resonant at 1100 cycles. When 30 current is received at some other frequency, however, the shunt-resonant condition is not present at coil 1219 and the associated shunt tuning condensers, permitting current to pass through condenser 1218 by way of coil 1219 and the associated 35 shunt condensers. The value of condensers 1218 is so chosen that it (connected in multiple with tuning condenser 1220 through the system composed of coil 1219 and its associated condensers) causes the coil 1221 to have a resonant peak at 900 cycles, in addition to the previously 40 described one at 1100 cycles.

The way in which the triple-peak tuning arrangement operates to control the impulse amplifier 1213 by way of the differential detector 45 1212 will now be pointed out:

It is to be noted that the control grid of the impulse amplifier 1213 is normally provided with a negative grid bias of 20.1 volts by virtue of its connections to the heater circuit, which amount 50 represents the drop across the heaters of tubes 1213, 1212, and 1211, in addition to the drop across the 4-ohm resistor 1225. This grid biasing potential is supplied to the control grid of tube 1213 through the center-tapped .6-megohm 55 resistor comprising sections 1229 and 1230. Each section of this resistor is by-passed by .1 mf. storage condenser, as shown. By virtue of the connection of conductor 1244 to the center tap of the grid resistor associated with impulse amplifier 1213, and the connection of the lower terminal 60 of this resistor to the heater circuit at a point of negative 20.1 volts, a negative potential of 20.1 volts is normally maintained on the two plates of the differential detector 1212 through 65 coils 1221 and 1223. The cathode associated with the plate connected to the 1000-cycle coil 1223 is also supplied with a biasing potential of negative 20.1 volts, whereby there is normally no potential difference between the cathode and 70 anode of tube 1212 with respect to coil 1223.

The cathode associated with the double-peak coil 1221 (resonant at 900 cycles at 1100 cycles) is connected to the heater circuit at a point of negative 1.2 volts potential, whereby the plate 75 connected to coil 1221 is normally 18.9 volts more

negative than the associated cathode, by virtue of which fact no current passes through the left-hand portion of the differential detector until the rather substantial adverse bias of 18.9 volts is overcome.

During the reception of a signal, the building up of a 1000-cycle potential across coil 1223 causes current to flow through the associated cathode and anode of tube 1212 in series with the section 1229 of the grid resistor. Thus half-wave-rectified current passes through the upper section of 1229 of the resistor and renders the upper terminal of this resistor section more positive than the lower terminal, thereby offsetting to this extent the negative potential normally applied to the control grid of impulse amplifier 1213. On the other hand, when the signal contains a sufficient component at 900 cycles or 1100 cycles to cause a sufficient potential to be built up across coil 1221 to overcome the 18.9 volts bias, current flows in the left-hand section of the differential detector 1212. This half-wave-rectified current passes through the lower section 1230 of the grid resistor associated with the tube 1213, causing the mid-point of this resistor to become more negative than the lower terminal thereof by virtue of the potential drop through section 1230. Therefore, when a signal other than a wanted signal is received and which falls in the neighborhood of 900 cycles or 1100 cycles, the current flowing through coil 1221 and the associated section of the differential detector and obtained through the section 1230 of the grid resistor associated with tube 1213, tends to render the grid of tube 1213 more negative than it normally is, thereby preventing a response at tube 1213 to the signal, even though sufficient current may flow through coil 1223 to otherwise secure a response.

It is to be noted that pulse-cut-in relay 1204 is provided to be controlled over pulse-cut-in conductor 1166. When the tone unit is to be used to receive dial impulses from a distant exchange, relay 1204 is operated to substitute incoming-impulse relay 1203 for retard coil 1207 in the plate circuit of impulse amplifier 1213. The previously mentioned grid bias normally existing on the control grid of tube 1213 is sufficient to block the flow of current from the 130-volt source of plate current. However, when a signal is received which causes the potential on the control grid of tube 1213 to be brought down to a negative value of about sixteen volts, current starts to flow through the tube, it being noted that the screen grid and suppressor grid of this tube are connected to the plate to secure a triode of the desired characteristics. As the potential of the control grid is rendered still less negative, relay 1203 operates when about 4.5 milliamperes of current are flowing in the plate circuit, about 9 milliamperes being preferable for operating the relay reliably during the reception of dial pulses.

A fairly constant response of incoming impulse relay 1203 over a wide range of input voltage is inherent in the disclosed arrangement because of the tendency of the grid-cathode circuit of tube 1213 to draw a grid current when the input signal voltage is sufficiently high to overcome the normal biasing voltage of negative 20.1 volts. This characteristic of the tube imposes a rather definite limit on the swing of the grid toward a positive-potential value, permitting a fast recovery of the negative blocking potential between signal pulses. Keeping in mind that the coil 1223 and the associated tuning condensers 1222 com-

prise a resonant couple having the maximum response at 1000 cycles, but not sharply peaked, the double-peak coil 1221 associated with the left-hand section of the double-diode tube 1212, 5 offers an opposing effect to afford definite frequency-cut-off points above and below the desired 1000-cycle resonant point, while there is a rather flat frequency response over the selected band. This band is about 120 cycles wide in order to provide for the reception of 60-cycle-modulated, 10 1000-cycle signal impulses.

By arranging that the response curve of the coils 1221 and 1223 intermingle (coil 1221 peaks at 900 and at 1100 but still builds up an appreciable voltage at 1000 cycles) the voltage built up across the double-peak coil 1221 at the 1000-cycle signal frequency and over the upper portion of the signal-strength range is sufficient to reduce considerably the positive grid-swing tendency, 15 thereby further tending to secure a uniform response over a wide range of input voltage. The weak signals, however, are not handicapped by the opposing effect of coil 1221, as the adverse bias is not then overcome.

20 The signal amplifier 1214 is provided to amplify the 60-cycle modulations received at the plate of impulse amplifier 1213. The control grid of the tube 1214 is provided with a normal negative biasing potential of 20.1 volts through the 25 100,000-ohm grid resistor 1232. At this biasing voltage, substantial plate current flows through the plate circuit of the tube through the plate impedance coil 1208 from the 130-volt source of plate current, the screen grid of this tube being connected directly to the source of plate current 30 while the suppressor grid is connected directly to the cathode to provide the usual form of pentode operation. The .1 mf. coupling condenser 1231 serves to couple the plate of tube 1213 with the control grid of tube 1214, to transmit the 60-cycle signal impulses to the signal amplifier.

35 After amplification by tube 1214, the signal impulses pass to the incoming-signal relay 1205 by way of the .3 mf. condenser 1234. Condenser 1234 and the winding of relay 1205 are so chosen that the circuit containing them is series resonant at about 60 cycles, whereby the incoming signal responds vigorously to 60-cycle current, but 40 does not respond when the 1000-cycle dial impulses, following each other at about ten to fourteen impulses per second, are received.

45 The .006 mf. condenser 1235 is provided to bypass amplified, half-wave-rectified 1000-cycle carrier current from relay 1205, as it is found in practice that otherwise amplified 1000-cycle potential is sufficiently high to cause undesired brush discharges.

50 With the tone unit in normal position direction-transfer relay 1202 is operated over direction-transfer conductor 1165. Also, pulse-cut-in relay 1204 is in restored condition, whereby incoming impulse relay 1203 is out of circuit and the retard coil 1207 is in circuit. This is the 55 condition in which the tone unit receives a 60-cycle-modulated seizing pulse when the associated toll line is taken for use at the distant end. This pulse comes into the tone unit through the receiving conductors 1162 and passes through the 60 transformer 1224 to the grid-cathode circuit of the two-way amplifier tube 1211. The signal is amplified and passes through condenser 1226 to the primary winding of transformer 1217. From the secondary winding of this transformer, the 70 signal passes through contacts of the normally 75

operated direction-transfer relay 1202 to the leads 1243 and 1244 associated with the tuning coils. This signal then passes through the differential detector 1212 to the control grid of the impulse amplifier 1213, passing thence by way of coupling condenser 1231 to the control grid of the signal amplifier 1214. The incoming-signal relay 1205 responds to the flow of alternating current through its winding in series with the condenser 1234, the condenser 1234 and the winding of the 10 relay being substantially resonant to the 60-cycle modulating frequency. Upon responding, incoming signal relay 1205 extends ground potential for the duration of the signal over the signal-in conductor 1163. Relay 1205 restores and again removes ground potential from conductor 1163 when the seizing pulse is terminated.

15 When the associated repeater responds to the seizing pulse and actuates the pulse-cut-in relay 1204 over conductor 1166, incoming pulse 20 relay 1203 is substituted for plate impedance coil 1207. As a result, when the dial pulses of unmodulated 1000-cycle current arrive, these impulses pass through as above explained to the incoming signal relay 1205, but this relay does 25 not respond at this time because the frequency of the pulses does not correspond to the frequency to which the coil of relay 1205 and the condenser 1234 are resonant. Relay 1203 is operated momentarily upon the receipt of each 30 of these dial pulses, momentarily grounding the dial-in conductor 1164 each time it operates.

35 When the pulse-cut-in relay 1204 is subsequently restored by the associated repeater, incoming-impulse relay 1203 is removed from circuit and plate-impedance coil 1207 is reintroduced, preventing further response of relay 1203, while permitting incoming signal relay 1205 to respond to any further received current at carrier frequency which is modulated at the pre-determined 60-cycle rate.

40 When the tone unit is to be used to transmit a seizing pulse over the associated toll line, direction-transfer relay 1202 is restored to transfer the grid of the tube 1211 from the upper terminal of coil 1224 to the 1000-cycle control lead 1242. When this occurs, a 1000-cycle variation is caused to be produced in the plate current normally passing through plate impedance coil 1206. At the same time, the suppressor grid of the tube 1211, the grid lying just within the plate or anode element of the tube, is extended 45 through contacts of the non-operated relay 1201 to the 40-volt, 60-cycle modulation lead 1241. On each negative half cycle of the potential on lead 1241, the current-flow through the tube 1211 is caused to cease altogether, while on each positive half cycle the current is permitted to flow unimpeded. In this way, sixty uniformly separated pulses of 1000-cycle current are caused 50 to flow through the plate circuit of tube 1211 each second. These pulses are permitted to pass through the coupling condenser 1226 to the primary winding of transformer 1217. The secondary winding of transformer 1217, with relay 1202 55 restored, is connected to the sending conductors 1161, while the mid-point of this winding is grounded for purposes having to do with line stabilization. The sending conductors 1161 are suitably connected with the toll line through the 60 associated impulse repeater to permit the 60-cycle modulated 1000-cycle current to pass over the toll line.

70 At the end of the transmission of the seizing pulse, direction-transfer relay 1202 may be per- 75

mitted to reoperate to return the tone to the normally existing receiving condition.

In order to prepare for the transmission of series of unmodulated 1000-cycle pulse, modulation-cut-off relay 1201 may be operated over modulation cut-off conductor 1167 to thereby connect the associated back contact of the concerned armature of relay 1202 to ground instead of to modulation conductor 1241. In this way, 10 when direction-transfer relay 1202 is next restored, unmodulated 1000-cycle current flows from the tube 1211 through coupling condenser 1226 to the transformer 1217, and passes through this transformer, through contacts of the restored 15 relay 1202, to the sending leads 1161. This 1000-cycle current is suitably impressed through pulsing contacts of the impulse repeater on the conductors of the toll line.

The modulation-cut-off relay 1201 may be 20 again restored after the dial pulses have been transmitted to permit the transmission of further 60-cycle-modulated, 1000-cycle current, the varying control of the relay 1201 and 1202 being as explained in the Wicks patent and in the 25 Wicks application referred to hereinbefore.

In the event that it is desirable during repair or test of the unit to open the heater circuit, the key 1237 may be restored for this purpose. Additional contacts of key 1237 open a point in the 30 circuit of lamp 1236 to avoid lighting this trouble-signal lamp upon the restoration of test relay 1233, which occurs when the heater circuit is opened.

In the event that it is desired to test the 35 transmission level of the tone unit, the key 1234 may be actuated and a test plug associated with the test equipment may be inserted into the jack 1215, connected to the sending leads 1161. Upon the actuation of key 1234 direction-transfer relay 1202 is restored and modulation-cut-off relay 1201 is operated. In the event that the transmission level is not satisfactory, it may be adjusted by moving the slide arm of the adjustable 40 shunt resistor 1216.

45 When the test and adjustment have been accomplished, the plug may be removed from the jack 1215 and the key 1234 may be restored. Upon the restoration of this key, relay 1202 is permitted to reoperate and relay 1201 is permitted 50 to restore.

The connection between the control grid of tube 1211 and the 1000-cycle conductor 1242 includes an additional armature spring of relay 1202, as shown, instead of the simpler arrangement of 55 connecting conductor 1242 directly to the back contact of the armature of relay 1202 which is connected to the contact grid. This arrangement further reduces the inter-contact capacity which may otherwise be sufficient to impress a slight local 1000-cycle modulation on the control grid with relay 1202 operated. This tendency is rendered practically non-existent by the grounded 60 front contact of the intermediate armature under discussion.

65 What is claimed is:

1. In a signalling system wherein received modulated carrier current is rectified to produce direct current, a responding relay arranged to respond to impulses of rectified carrier current 70 to repeat corresponding signal pulses into a local circuit, a circuit resonant at the modulation frequency of the received carrier current, a signal relay responsive to the flow of resonant current in said resonant circuit, an amplifying device for supplying power to said resonant circuit, and cir-

cuit connections for supplying input power to said amplifying device from the circuit of the first named relay.

2. In combination, a source of alternating current signals, a conductor on which said signals are to be impressed, a first rectifier associated with said source for impressing rectified signal potentials on said conductor, a second rectifier interconnected with said conductor and effective to draw current from said conductor to reduce 10 the potential thereon, means for impressing a biasing potential opposing the drawing of current from said conductor except when the rectified potential thereon is sufficient to overcome the biasing potential, a responding device, and 15 means for causing said device to respond to signals according to the potential existing on said conductor.

3. In combination, an electron discharge device including input and output electrodes, an 20 output circuit coupled to said output electrodes, a tuned circuit having a frequency response characteristic which peaks at a predetermined frequency, a tuned circuit having a frequency response characteristic which peaks at frequencies 25 respectively above and below said predetermined frequency, said tuned circuits being adapted to be coupled to a source of signal currents, means for impressing a direct voltage between said input electrodes which is controlled in accordance 30 with the signal voltage across one of said tuned circuits, and means for impressing a direct voltage between said input electrodes which is controlled in accordance with the signal voltage across the other of said tuned circuits and which is in opposition to said first-named direct voltage, whereby the current in 35 said output circuit is controlled in accordance with the difference in magnitudes of the signal voltages across said tuned circuits.

4. In combination, an electron discharge device including input and output electrodes, a tuned circuit having a response characteristic which peaks at a predetermined frequency, a tuned circuit having a response characteristic which peaks at frequencies substantially equally spaced respectively above and below said predetermined frequency, the peak frequencies of said last-named tuned circuit being displaced substantially equally on either side of said predetermined frequency, means for impressing a direct voltage between said input electrodes which is controlled in accordance with the signal voltage across one of said tuned circuits, and means for impressing a direct voltage between said input 50 electrodes which is controlled in accordance with the signal voltage across the other of said tuned circuits and which is in opposition to said first-named direct voltage, whereby the current in said output circuit is controlled in accordance 55 with the difference in magnitudes of the signal voltages across said tuned circuits.

5. In combination, an electron discharge device including input and output electrodes, an output circuit coupled to said output electrodes, 60 a tuned circuit having a frequency response characteristic which peaks at a predetermined frequency, a tuned circuit having a frequency response characteristic which peaks at frequencies respectively above and below said predetermined 65 frequency, said tuned circuits being adapted to be coupled to a source of signal currents, and a network including rectifying means interconnecting said tuned circuits and said input electrodes, said network being so connected and ar- 70

ranged that a direct voltage, variable in accordance with the signal voltage across said first-named tuned circuit, is impressed on said input electrodes, and a second direct voltage, opposed to said first direct voltage and variable in accordance with the voltage across said second-named tuned circuit, is impressed on said input electrodes, whereby the current in said output circuit is controlled in accordance with the difference in magnitudes of the signal voltages across said tuned circuits.

6. In combination, an electron discharge device including input and output electrodes, an output circuit coupled to said output electrodes, a tuned circuit having a frequency response characteristic which peaks at a predetermined frequency, a tuned circuit having a frequency response characteristic which peaks at frequencies respectively above and below said predetermined frequency, said tuned circuits being adapted to be coupled to a source of signal currents, means normally biasing said device beyond cut off, means for impressing a direct voltage between said input electrodes which varies in accordance with the signal voltage across said first-named tuned circuit, whereby a current in said output circuit is only produced when the signal voltage across said first-named tuned circuit attains a substantial value, and means for impressing a direct voltage between said input electrodes which varies in accordance with the signal voltage across said second-named tuned circuit and which is in opposition to said first-named direct voltage whereby the current in said output circuit is controlled in accordance with the difference in magnitudes of the signal voltages across said tuned circuits.

7. In combination, an electron discharge device including input and output electrodes, an output circuit coupled to said output electrodes, a tuned circuit having a frequency response characteristic which peaks at a predetermined frequency, a tuned circuit having a frequency response characteristic which peaks at frequencies respectively above and below said predetermined frequency, said tuned circuits being adapted to be coupled to a source of signal currents, means normally biasing said device beyond cut off, means for impressing a direct voltage between said input electrodes which varies in accordance with the signal voltage across said first-named tuned circuit, whereby a current in said output circuit is only produced when the signal voltage across said first-named tuned circuit attains a substantial value, and means for impressing a direct voltage between said input electrodes which varies in accordance with the signal voltage across said second-named tuned circuit and which is in opposition to said first-named direct voltage, whereby the current in said output circuit is controlled in accordance with the difference in magnitudes of the signal voltages across said tuned circuits, said second-named tuned circuit having a substantial response at said predetermined frequency, whereby said second-named direct voltage assists said biasing means in maintaining the current in said output circuit at a negligible value until the signal voltage across said first-named tuned circuit attains said substantial value.

8. In combination, an electron discharge device including input and output electrodes, an output circuit coupled to said output electrodes, a biasing network connected between said input electrodes, a tuned circuit having a frequency

response characteristic which peaks at a predetermined frequency, a tuned circuit having a frequency response characteristic which peaks at frequencies respectively above and below said predetermined frequency, said tuned circuits being adapted to be coupled to a source of signal currents, a rectifier coupled to said first-named tuned circuit and connected to impress its rectified output voltage across at least a portion of said biasing network, and a second rectifier coupled to said second-named tuned circuit and connected to impress its rectified output voltage across at least a portion of said biasing network in opposition to said first-named rectified voltage, whereby the current in said output circuit is controlled in accordance with the difference in magnitudes of the signal voltages across said tuned circuits.

9. In combination, an electron discharge device including input and output electrodes, an output circuit coupled to said output electrodes, a biasing network connected between said input electrodes, a tuned circuit having a frequency response characteristic which peaks at a predetermined frequency, a tuned circuit having a frequency response characteristic which peaks at frequencies respectively above and below said predetermined frequency, said tuned circuits being adapted to be coupled to a source of signal currents, a source of biasing voltage connected to said biasing network and normally effective to bias said device beyond cut off, a rectifier coupled to said first-named tuned circuit and connected to impress its rectified output voltage across at least a portion of said network in opposition to said biasing voltage, and a second rectifier coupled to said second-named tuned circuit and connected to impress its rectified output voltage across at least a portion of said network in opposition to said biasing voltage, and a second rectifier coupled to said second-named tuned circuit and connected to impress its rectified output voltage across at least a portion of said network in the correct phase to boost said biasing voltage, whereby a current in said output circuit is only produced when the signal voltage across said first-named tuned circuit attains a substantial value and the current in said output circuit is controlled in accordance with the difference in magnitudes of the signal voltages across said tuned circuits.

10. A signal receiving device comprising, in combination, an inductance element, means comprising a capacitor for tuning said element to resonance at a predetermined frequency, means comprising a second capacitor for tuning said element to resonance at a second frequency, and means comprising a circuit resonant at said predetermined frequency for preventing said second-named capacitor from substantially affecting the response of said device at said predetermined frequency.

11. A signal receiving device comprising, in combination, an inductance element, a capacitor connected in series with said inductance element to tune said element to resonance at a predetermined frequency, a second capacitor connected in series with said element to tune said element to resonance at a second frequency which is substantially lower than said predetermined frequency, and means comprising a parallel resonant circuit tuned to said predetermined frequency and connected between said inductance element and said second-named capacitor for preventing said second-named capacitor from substantially affecting the response of said device at said predetermined frequency.

12. A signal receiving device having input terminals and comprising, in combination, a pair of

- reactance elements having opposite frequency-current characteristics connected in series between said terminals, said elements having their reactance values so proportioned that the circuit formed thereby is resonant at a predetermined frequency, and a network shunting one of said elements, said network comprising a reactance element of the same type as said one element and a parallel resonant circuit connect-
5 ed in series, the reactance values of the elements of said network being so proportioned relative to each other that the series impedance thereof is substantially infinite at said predetermined frequency and that the combined circuit formed
10 by the other of said pair of elements and said network is resonant at a second frequency different from said predetermined frequency.
15 13. A signal receiving device having input terminals and comprising, in combination, a pair of reactance elements having opposite frequency-current characteristics connected in series between said terminals, said elements having their reactance values so proportioned that the circuit
20

formed thereby is resonant at a predetermined frequency, a network shunting one of said elements, said network comprising a reactance element of the same type as said one element and a parallel resonant circuit connected in series, 5 the reactance values of the elements of said network being so proportioned relative to each other that the series impedance thereof is substantially infinite at said predetermined frequency and that the combined circuit formed by the other 10 of said pair of elements and said network is resonant at a second frequency different from said predetermined frequency, and a second circuit connected between said terminals, said second circuit comprising a pair of reactance elements 15 having opposite frequency-current characteristics connected in series and having their reactance values so proportioned that said second circuit is resonant at a frequency substantially intermediate said predetermined frequency and 20 said second frequency.
